ENGINE PRIMING MEANS

Wright A. Parkins, West Hartford, and Alfred H. Marshall, West Bloomfield, Conn., assignors, by mesne assignments, to United Aircraft Corporation, a corporation of Delaware

Application June 23, 1933, Serial No. 677,214

5 Claims. (Cl. 123—187.5)

This invention relates to an improvement in priming means adapted primarily for use with internal combustion engines, and is shown as applied on a type of engine adapted to be used in aircraft.

It is sometimes desirable to inject fuel into the cylinders or into a passage leading to the cylinders of an internal combustion engine to assist in quickly starting the engine. It is always desirable, however, to reduce the number of parts required to operate an engine and also to keep the fuel which is often highly inflammable out of the compartments occupied by the passengers in a vehicle and especially is this true in the aircraft industry.

With these features in mind, an object of this invention is to provide means for priming an engine.

Another object of this invention is to provide such priming means without bringing the priming fluid into the passenger compartments.

Still another object of this invention is to provide an engine priming means which shall be simple, compact and when added on to engine will require but a small amount of additional mechanism.

Further and other objects and advantages will be apparent from the specification and claims and from the accompanying drawings which illustrate what is now considered the preferred embodiment.

Fig. 1 is a side elevation of an engine showing the priming means attached thereto.

Fig. 2 is a diagrammatic sketch showing the priming means and its connections.

Fig. 3 is a side view of an airplane with the priming device installed.

Fig. 4 is a detailed view of the pump and valve operating mechanism.

Fig. 1 shows the outline of an engine adapted for aircraft use and having a crankcase 20 and cylinder 22. The propeller hub has been indicated by the numeral 24 and the blower section by the numeral 26. Fuel is supplied to the engine from carburetor 28, passing through conduit 30, rear section 32, blower section 26 and intake pipe 34, and thence into cylinder 22. The carburetor is supplied with a throttle valve and its operating lever, indicated by numeral 36, and with an accelerating pump 38. The accelerating pump is connected with the throttle mechanism by a connection 40 so that operation of the throttle lever 36 will operate the accelerating pump. The carburetor is also supplied with a lever 42 which is adapted to change the ratio of fuel to air in the

mixture produced by the carburetor which lever is commonly known as a mixture control lever. The mechanism thus far described is a standard commercial engine and carburetor.

A valve 44, having an operating lever 45 secured thereto, is provided preferably in the carburetor housing and is operatively connected to the mixture control lever 42 by a link 46 so that operation of the mixture control lever will cause operation of the valve 44. The accelerating pump 38 is adapted to inject fuel into the mixture passage or conduit 30 of the carburetor during opening movements of the throttle valve so that when the engine is running and the throttle valve is suddenly opened, a richer mixture will be temporarily supplied to the engine. In the device illustrated, movements of the throttle lever 36 to open the throttle will cause a downward movement of the connection 40 and the accelerating pump plunger 48. This will cause fuel entrapped in the space 50 to be forced through the conduit 52, valve 44, conduit 54 and out through the accelerating jet 56 into the conduit 30.

The valve 44 is adapted to be turned into a position such that communication is established between conduit 52 and conduit 58. When the valve is turned to this last named position, actuation of the accelerating pump plunger will cause fuel entrapped in the space 50 to be forced through conduit 52, valve 44, conduit 58 and into the cylinder 22. If it is not convenient or desirable to inject the fuel directly into the cylinder 22, it may be injected into an intake conduit adjacent the cylinder, such as conduit 34, or it may be injected into the blower section 26. It will thus be seen that by proper manipulation of the valve 44, the engine may be primed by actuation of the accelerating pump.

The valve 44 may be operated by any convenient mechanism and in the embodiment illustrated it is operated by movement of the mixture control lever 42. When the mixture control lever is placed in what is commonly known as "full lean" position, shown in dotted lines in Fig. 1, the valve lever 45 is turned to the position shown in dotted lines in Fig. 1 thus turning the valve 44 to connect conduit 52 with the conduit 58. In all other positions of the mixture control lever, the valve 44 connects the conduit 52 with the conduit 54 so that the carburetor operates in its usual manner. It will thus be seen that we have provided a priming device that is simple in construction and overcomes many of the disadvantages of the present priming devices.

In the usual construction, the engine is placed

in a compartment or portion of a vehicle commonly called the engine compartment and indicated by reference numeral 66 in Fig. 3. In aircraft, and particularly in airplanes, the engine compartment is separated from the pilot's and/or the passenger compartment, indicated by reference numeral 68 in Fig. 3, by a partition known as a fire wall, and the engine controls are extended through this fire wall to a position within convenient reach of the pilot or operator. In the accompanying drawings, we have shown this partition separating the engine and pilot's compartment as a wall 60 and have indicated the throttle valve control means, which also operates the fuel pump, as a rod 62, and the mixture control means, which also operates the valve 44, as a rod 64.

The operation of this device is as follows in starting an engine. The mixture control lever 20 is set at "full lean", thereby operating the valve 44 so as to connect the accelerating pump with the priming connection. The throttle rod 62 is then oscillated several times as in opening and closing the throttle, thereby actuating the accelerating pump plunger 48 to inject fuel into the priming connections. The mixture control is then set to the desired starting position, and the engine crank shaft rotated in the usual manner. It will thus be seen that we have provided a device which is also simple in operation as well as simple in construction. As it is usual, especially in aircraft practice, to bring an operating connection from the mixture control lever to the driver's compartment and also bring a connection from 35 the throttle lever to the driver's compartment, it is apparent that we have provided an efficient priming device without bringing any additional controls, or any fuel connections into the driver's or passenger's compartment.

40 It is to be understood that the invention herein described is not limited to the specific embodiment illustrated and described but may be used in various other forms without departure from its spirit, as defined by the following claims.

45 What we claim as new and desire to secure by Letters Patent is:

1. In combination with an engine, a carburetor having a fuel pump, a jet, and mixture control operating means, an engine priming connection, 50 a valve for selectively directing fuel from said pump to said jet or to said engine priming connection and means connecting said mixture control operating means and said valve whereby operation of the mixture control operating means 55 will operate the valve.

2. In combination, means comprising a carburetor having a throttle valve, an accelerating

5 pump operatively connected therewith, an accelerating jet, an engine priming connection, and a valve adapted to direct fuel from said pump to either said accelerating jet or said priming connection, mixture control operating means associated with said carburetor, and means operatively connecting said mixture control operating means and said fuel directing valve, a single means for operating said throttle valve and said accelerating pump, and a single means for 10 operating said mixture control operating means and said fuel directing valve.

3. In combination with an engine, a carburetor, a fuel conduit between said carburetor and said engine, a throttle valve in said carburetor, manually controllable means for actuating said throttle valve, a mixture control valve, manually controllable means for actuating said mixture control valve, and a pump actuated by said throttle valve actuating means to supply a 20 metered quantity of additional fuel to said engine on opening movement of said throttle valve, a three-way valve connected with the outlet of said pump, a conduit connecting said three-way valve with said carburetor, a second conduit connecting 25 said three-way valve with said fuel conduit, and a connection between said three-way valve and said mixture control valve actuator for actuating said three-way valve to selectively direct the fuel discharged from said pump into said first 30 mentioned conduit or into said second mentioned conduit.

4. In a carburetor for a multi-cylinder internal-combustion engine provided with an intake manifold, a throttle actuated acceleration pump, a 35 mixture control valve, a branched outlet from said acceleration pump having one branch leading to the mixing chamber of the carburetor and the other branch leading to the engine cylinder adjacent the connections with the intake 40 manifold, a valve for selectively connecting the acceleration pump with either of said branches, and common manual means for simultaneously actuating said valves.

5. In an internal combustion engine, a manifold, a carburetor including a main induction passage, a throttle valve controlling the induction passage, a fuel reservoir, an acceleration pump for supplying fuel to the induction passage anterior to the throttle valve when the throttle is 50 moved in the opening direction, connecting means between the acceleration pump and the manifold, and valve means for directing the fuel supplied by the acceleration pump to the manifold under certain operating conditions.
